(57) **CLAIM**

The ornamental design for a lamp, as shown and described.

DESCRIPTION

FIG. 1 is a right side perspective view of a lamp showing our new design;

FIG. 2 is a top, front, and left side perspective view thereof;

FIG. 3 is a bottom, rear, and right side perspective view thereof;

FIG. 4 is a bottom, front, and left side perspective view thereof;

FIG. 5 is a left side perspective view thereof;

FIG. 6 is a front perspective view thereof;

FIG. 7 is a rear perspective view thereof;

FIG. 8 is a top plan view thereof;

FIG. 9 is an enlarged fragmentary top, front, and right side perspective view thereof, with portions omitted for clarity of illustration; and,

FIG. 10 is an enlarged bottom, front, and left side perspective view thereof, with portions omitted for clarity of illustration. The broken line disclosure represents portions of the Lamp with form no part of the claimed design.
